[57] **CLAIM**

The ornamental design for a pressure point applicator, as shown.

DESCRIPTION

FIG. 1 is a perspective view of a pressure point applicator, showing my new design, with one side of the applicator fragmentarily shown for ease of illustration; FIG. 2 is a bottom perspective view thereof;

FIG. 3 is a top plan view of the complete pressure point applicator;

FIG. 4 is a side elevational view thereof in the direction arrow 4 of FIG. 3, the opposite side elevational view being identical thereto;

FIG. 5 is a bottom plan view thereof; in the direction of arrow 5 of FIG. 4; and,

FIG. 6 is an end elevational view thereof; in the direction or arrows 6 of FIG. 4; the opposite end elevational view being identical thereto.

FIG. 1
